FUEL SUPPLY INDICATOR FOR
REFRIGERATORSMarc Resek, Cleveland Heights, Ohio, assignor to
Perfection Stove Company, Cleveland, Ohio, a
corporation of Ohio

Application July 20, 1932. Serial No. 623,562

10 Claims. (Cl. 62—118)

This invention relates to intermittent absorption refrigerators of the class in which the generator is heated by means requiring the supplying of a heating medium thereto at given intervals 5 of time, according to a prescribed schedule of operation. For example, the generator may be heated by a liquid fuel combustion device that is supplied on the occasions of filling and lighting with just enough fuel to sustain a so-called heating 10 period by which a cycle of operation is initiated, the fire going out when the fuel supply is exhausted; wherefore, excepting for the filling and lighting performances or equivalent manual operation, the action of the apparatus is automatic.

Broadly, the invention consists of means for indicating according to the condition of the cooling unit or the temperature of the refrigeration compartment at the conclusion of a cycle of operation the heat or fuel requirement for the subsequent heating period. By virtue of the invention, as will be readily seen, chilling of the refrigeration compartment to too low a temperature may be avoided, and the consequential liability of 25 injury to food stuffs prevented.

The invention may be said to have as its primary purpose the provision of reliable means for informing an attendant of a refrigerator of the above mentioned class as to the amount of heat 30 or quantity of liquid fuel needed on the occasions of starting or filling and lighting in order to maintain a satisfactory refrigeration temperature.

Other objects are to provide means of the above character that is simple and inexpensive; whose 35 use is especially convenient, and the manner of which use is readily apparent from the nature of the device.

Objects and advantages additional to the foregoing will appear as I proceed to describe the embodiment of the invention illustrated in the accompanying drawings wherein Fig. 1 is a sectional front elevation of an intermittent absorption refrigerator having my invention incorporated therein; Fig. 2 is a fragmentary sectional 45 side elevation showing the liquid fuel combustion device in operative relation to the generator; Fig. 3 is a detail, partly in section, of the liquid fuel dispensing receptacle or bottle inverted within the fuel cup of the combustion device; Fig. 4 is a sectional front elevation of the thermometer that forms a part of the invention, the same being shown considerably larger than actual size; Fig. 5 is a vertical section through the dispensing receptacle or bottle with the valved closure removed and in upright position as for filling, and Fig. 6 is a section on the line 6—6 of Fig. 5.

The refrigerator, designated generally by the reference numeral 1, consists of a cabinet enclosing an insulated refrigeration compartment 2 and, 60 to one side thereof according to the present em-

bodiment, a flue or combustion chamber 3. A condenser tank 4 surmounts the cabinet. Suitably supported within the flue or combustion chamber 3 is a vessel 5 that serves as a generator during the heating-condensing period, and as an absorber during the period of evaporation. 6 is a cooling unit or evaporator that is located within the upper portion of the cabinet in heat exchanging relation to the interior of the refrigeration compartment 2. A vapor delivery conduit 7 leads from the top of the vessel 5 to the bottom of a receiver 6^a that forms a part of the cooling unit or evaporator 6. A portion of the conduit 7 intermediate its ends is coiled within the tank 4, as shown at 7^a, and forms a part of the condenser. A gas return conduit 8 leads from the top of the cooling unit or evaporator 6—more specifically the receive 6^a thereof—to the bottom portion of the vessel 5. A liquid return tube 9, such as that constituting the subject matter of United States Letters Patent No. 1,816,975, dated August 4, 1931, leads from a low point or sump in the cooling unit or evaporator 6 to an elevation within the vessel 5 well below the maximum liquid level therein.

Supported within the flue or chamber 3 below the generator 5 (preferably in such manner that it may be slid in and out, and removed if desired) is a liquid fuel combustion device designated generally by the reference numeral 10. Briefly, this device consists of burners 11 that communicate, through a pipe 12, with a supply cup 13 into which a dispensing receptacle or bottle 14 is adapted to be inserted downwardly in inverted position. This receptacle or bottle has a neck 15, that serves as a filling, as well as a discharge, opening, to which a closure 16 is applied, the same being equipped with a valve 17 that is biased toward closed position by a spring 18, interposed between an abutment 19 on the stem 20 of the valve and an opposed portion of the closure 16. As will be readily seen from Fig. 3, when the receptacle or bottle 14 is supported in inverted position within the cup 13 by the engagement of a circumferential shoulder 21 of the receptacle with the rim of the cup, the stem 20 of the valve 17 will engage the bottom of the cup and lift the valve off its seat 22 that surrounds the discharge opening of the closure. A shield 23, shown as carried by the pipe 12, is disposed between the cup 13 and the adjacent burner 11.

25 is a thermometer that is adapted to be placed within the refrigeration compartment 2. While this thermometer may be of any approved type, the one herein disclosed which I find especially suitable for the purpose comprises the usual glass tube 26, containing a suitably colored liquid 27, and attached to a back 28 by clips 29. This structure, interposed between cushions 30, is enclosed within a glass receptacle 31, fitted

with a cap 32 that is equipped with a suspending means or hook 33. The back 28, according to the present embodiment, bears the following instructions: "Each day fill bottle with amount of oil 5 shown by red line at lighting time", and the indicia: "Full bottle"; "% Full", and "% Full". In the region of the "%", "%", and "Full" indications is the designation "Refrigeration zone". The thermometer may be suspended by means of 10 the hook 33 from one of the shelves 40 in the refrigeration compartment 2.

Referring again to the dispensing receptacle or bottle 14, especially as illustrated in Figs. 5 and 6, attention is called to a liquid level gauge 15 or indicator 35 that is located on the inside of the receptacle and includes steps 36 and 37. On the latter, as will be seen by reference to Fig. 6, is the designation "%", and on the former, "%". These correspond to the like designations on the 20 thermometer. In the manufacture of the receptacle 14, the liquid level gauge or indicator 35, shown in the present instance as formed from a piece or strip of relatively thin metal, is spot welded or otherwise secured to the inner 25 side of the peripheral wall of one of the sheet metal shells or sections from which the receptacle is made, before said sections are attached together as by a seam 38. The gauge or indicator is so located as to be easily observed 30 through the relatively large neck 15 that is suitably attached to the wall of the receptacle in register with an opening therein. After assembly, the receptacle is thoroughly tinned, according to my present preference.

35 Before describing the operation of the apparatus, it may be explained briefly that the system, comprising the vessel 5, cooling unit 6, and conduits 7, 8 and 9, is hermetically sealed and contains a suitable quantity of refrigerant liquor, the 40 same consisting of a refrigerant, such as ammonia, and an absorbent therefor, such as water, in proper proportions. At the beginning of the cycle of operation, all or practically all of the liquor is in the vessel 5. Preparatory to starting 45 the operation, the receptacle or bottle 14 is supplied with a suitable quantity of liquid fuel, such as kerosene, and it is then placed, in inverted position, within the cup 13, the combustion device preferably being withdrawn from 50 beneath the vessel 5 at this time. The burners 11 are then lighted and the combustion device is returned to its operative position.

Upon heat being thus supplied thereto, the liquid within the vessel 5 boils and the resultant 55 vapors, rising through the conduit 7, are liquefied in the condenser 4 and gravitate to the cooling unit or evaporator 6. By the time the fuel supply is exhausted, a charge of refrigerant, sufficient to maintain the desired temperature in the 60 compartment 2 until the subsequent lighting time, has been distilled over into the cooling unit or evaporator 6.

As is well known to those familiar with the subject, the pressure within the system is quite high 65 during the heating-condensing period just described, and upon cessation of the heat, the pressure drops and evaporation begins. As the anhydrous refrigerant within the cooling unit evaporates, the gas returns through the conduit 8 to the vessel 5 and is reabsorbed by the relatively 70 weak liquor therein. This phase of the operation continues until all, or practically, all of the liquid is returned from the cooling unit to the generator. Any residue liquid left in the cooling 75 unit at the conclusion of the evaporation period

is returned to the generator through the tube 9 according to the principle set forth in the patent hereinbefore referred to.

While, under the average run of conditions, as in summer heat, it is necessary to completely fill the dispensing receptacle or bottle 14, with fuel in order to insure proper refrigeration until the subsequent lighting time, there are circumstances under which such a supply of fuel would be too great and would result in too low a temperature in the refrigeration compartment, such as would freeze liquids and be liable to spoil vegetables and other food stuffs. For example, these circumstances would exist if the refrigerator were subjected to relatively low atmospheric temperatures.

Now by referring to the thermometer 25, which is suspended within the refrigeration compartment, the proper amount of fuel to be placed in the dispensing receptacle or bottle in order to maintain a proper temperature in said compartment may be immediately ascertained. If, for example, the temperature of the refrigeration compartment is sufficiently low to cause the indicating line of the thermometer to be opposite the designation "% Full", the attendant pours fuel into the receptacle or bottle until the level reaches the indication "%" therein. With this reduced amount of fuel, the combustion device will burn for a lesser length of time than it ordinarily does and a correspondingly less amount of refrigerant will be distilled over into the cooling unit. This lesser charge of refrigerant will result in reduced refrigeration which will allow the temperature of the refrigeration compartment to rise somewhat, and by supplying oil to the combustion device in accordance with the indications of the thermometer, the temperature may be maintained within the desired refrigeration zone.

Having thus described my invention, what I claim is:—

1. In an intermittent absorption refrigerator involving heating means requiring the supplying of the heating medium thereto at predetermined intervals of time according to a prescribed schedule, such intervals marking the beginnings of the cycles of operation; means subjected to and influenced by the condition of the cooling unit for indicating at the conclusion of one cycle the heating medium requirements of said heating means for the ensuing cycle.

2. In an intermittent absorption refrigerator involving heating means requiring the supplying of the heating medium thereto at predetermined intervals of time according to a prescribed schedule, such intervals marking the beginnings of the cycles of operation; a member bearing indicia as to heating medium requirements under various conditions of the cooling unit, and thermal means associated with said member and subjected to and influenced by the temperature of the refrigerator for indicating, at the conclusion of a cycle of operation, on said member the heating medium requirements of said heating means for the ensuing cycle.

3. In an intermittent absorption refrigerator fired by a combustion device requiring the supplying of fuel thereto at predetermined intervals of time, according to a prescribed schedule, incident to the starting of the cycles of operation; means subjected to and influenced by the condition of the cooling unit for indicating at the conclusion of one cycle the fuel requirements of said combustion device for the ensuing cycle.

4. In an intermittent absorption refrigerator fired by a combustion device requiring the supplying of fuel thereto at predetermined intervals of time, according to a prescribed schedule, incident to the starting of the cycles of operation; a member bearing indicia as to the fuel requirements of said combustion device under various conditions of the refrigerator, and thermal means associated with said member and subjected to and influenced by the temperature of the refrigerator, for indicating, at the conclusion of a cycle of operation, on said member the fuel requirements of said device for the ensuing cycle. 80
5. In an intermittent absorption refrigerator fired by a liquid fuel combustion device requiring fuel replenishing and lighting at predetermined intervals of time, according to a prescribed schedule, for starting the cycles of operation; means subjected to and influenced by the temperature of the refrigerator for indicating at the conclusion of one cycle the fuel requirements of said combustion device for the ensuing cycle. 85
6. In an intermittent absorption refrigerator fired by a combustion device requiring the supplying of fuel thereto at predetermined intervals of time, according to a prescribed schedule, incident to the starting of the cycle of operation; thermo-sensitive means actuated by the temperature of the refrigerator for indicating at the conclusion of a cycle of operation the approximate fuel requirements of said combustion device for the ensuing cycle. 90
7. In an intermittent absorption refrigerator fired by a liquid fuel combustion device and in- 95

cluding a dispensing receptacle for supplying fuel to said device in quantity sufficient only for the heating period of a cycle of operation; thermo-sensitive means actuated by the temperature of the refrigeration compartment for indicating at the conclusion of a cycle of operation the approximate amount of fuel to be placed in the dispensing receptacle for maintaining the subsequent heating period. 100

8. The combination with a refrigerator of the type having cycles of operation and requiring fuel for a heating medium, of a thermal indicator in the refrigerator and subjected to the temperature thereof and provided with indicia related to the amount of fuel to be used in a certain cycle and determined by the temperature in the refrigerator at the end of the preceding cycle. 105

9. The combination with a refrigerator of the type requiring fuel for a heating medium, of a thermal indicator in the refrigerator and subjected to the temperature thereof and provided with means actuated by said temperature for indicating the amount of fuel proper for producing a desired temperature. 110

10. The combination with a refrigerator of the type requiring fuel for a heating medium, of a thermal indicator in the refrigerator and subjected to the temperature thereof and provided with means actuated by the temperature in the refrigerator for indicating the amount of fuel proper for producing a desired temperature in a succeeding cycle. 115
